UNITED STATES PATENT OFFICE.

CHARLES H. LEWIS, OF NEW HAVEN, CONNECTICUT, ASSIGNOR TO THE ACME WIRE COMPANY,
OF HAMDEN, CONNECTICUT, A CORPORATION OF CONNECTICUT.

ARMATURE-WINDING MACHINE.

No. 887,106.

Specification of Letters Patent.

Patented May 12, 1908.

Application filed June 15, 1905. Serial No. 265,339.

To all whom it may concern:

Be it known that I, CHARLES H. LEWIS, of the city and county of New Haven and State of Connecticut, have invented new and useful Improvements in Armature - Winding Machines, of which the following is a full, clear, and exact description, when taken in connection with the accompanying drawings, which form a part thereof, and in 10 which—

Figure 1 represents a front elevation (partly broken away) of the main portion of a winding machine embodying the invention, Fig. 2, a plan view of the same, and a portion 15 of the guiding and tension device, Fig. 3, a central longitudinal vertical section through one of the armatures and the associated parts of the machine, Fig. 4, a side elevation (partly in section) of the guiding and tension devices, Fig. 5, a side elevation of one of the armature holders and one of the brackets of the machine, Fig. 6, a similar view of the bracket alone, Fig. 7, a reverse view of the 20 armature holder, Fig. 8, an end elevation of a part of the tension pulley and associated parts of the tension device, Fig. 9, a transverse horizontal section on line 9—9 of Fig. 8, and Fig. 10, a central longitudinal section through the handle of the guiding mechanism.

In all figures, similar letters of reference represent like parts.

This invention relates to machines for winding wire on armatures, and has for one 35 of its objects the production of a machine by which a plurality of armatures may be wound simultaneously, and in which the wire is guided and the tension regulated automatically.

To this and other ends, the invention consists of the several improvements and combinations of parts set forth and claimed hereinafter.

For a more particular description of the 45 invention reference is had to the accompanying drawings, in which the parts designated by the letter A represent armatures and B the wire or wires being wound thereon. Each of the armatures A is held between a pair of blocks or holders C and F, having substantially rectangular concavities or depressions D, into which the side plates E of the armatures are adapted to fit snugly, as shown more particularly in Figs. 3 and 5, so that on

the rotation of the armature holders C and F, 55 the armature A is rotated therewith.

The end holder F of the series is shown provided with a tapering shaft or spindle G, adapted to be forced home into a socket H in a rotary shaft I, shown driven by the pulley 60 J. The intermediate holders C are rigidly mounted on short shafts or spindles K, which as shown in Fig. 3, connect adjacent holders of different pairs to rotate together. This spindle K has a bearing in an axial perforation L in a ring M, mounted on ball bearings N, within a stationary bracket O. Each bracket O is provided with one or more projections P, and is held from rotation by means of rods or wires Q, which extend 65 through perforations in the projections P, and terminate in a rigid support R. The brackets O are thus supported on the rods Q, and are prevented thereby from rotary movement, but are capable of longitudinal 70 sliding movement on the rods. Coiled springs S are mounted on the rods between adjacent brackets and tend to force the brackets apart. Each armature is held in place by being gripped by two holders C, and 75 the series of armatures is held by locking the end holders so that the brackets cannot spread apart. When, however, it is desired to remove the armatures it is only necessary to remove one of the end holders, whereupon 80 the springs S will force the brackets apart and separate each pair of holders, so that the armature carried thereby may be removed. The rotary movement of the shaft I is communicated to each armature by means of the 85 spindle G and end holder F, through the armature A, to the other holder C of the first pair. As each holder C is rigidly connected to the adjacent holder of the next pair on the opposite side of its supporting bracket, the 90 rotary movement of each of these holders is communicated to the next adjacent holder.

The wire B for each of the armatures passes over one pulley T from under another 100 pulley U, mounted on a support V, pivotally secured to an upright W. A series of these uprights W and pulleys are mounted on a sleeve Y at distances corresponding to the relative distances between the armatures. 105 The sleeve Y is loosely mounted on a stationary shaft Z, and is provided with two arms A' and B', having at their ends teeth adapted

to engage a threaded rotary shaft C', operated by a pulley D', driven by a belt E' from the pulley J. The thread on the shaft C' is divided, as shown in Fig. 2, and one part is a 5 left hand screw, and the other a right hand screw. One arm, as A', is adapted to engage one of the portions of this thread, and B' to engage the other portion. The arms extend, as shown in Fig. 4, on opposite sides of the 10 shaft C', and their ends are further apart than the diameter of the threaded shaft C'. By this construction, only one of these arms will engage the shaft at the same time, and both may be removed simultaneously if 15 desired. A lever F' is rigidly connected to the sleeve Y to rotate the sleeve to engage one arm and release the other from engagement with the shaft C' when desired. The end of the lever F' projects into the hollow 20 interior G' of a handle H'. A coiled spring I' in the interior G' bears at one end against the handle H' and at the other end against a washer J' rigidly mounted on the lever F'. The handle H' is provided with two studs K' 25 and L', one shown above and one below the lever F'. When one of these studs, as K', engages a bracket M' (Figs. 2 and 4), the lever F' and sleeve Y are swung so that the arm A' engages the screw C'. When it is 30 desired to engage the other arm B', the handle H' is drawn outward against the tension of the spring I', so that the lug K' is disengaged from the bracket M'. The lever and handle are then forced downward, and 35 the lug L' adapted to engage the under side of the bracket M', in which position the sleeve Y will have been rotated sufficiently to bring the arm B' into engagement with the screw threaded shaft C'. The wire B 40 before passing to the pulleys U and T from the spool N' passes over a tension pulley O', mounted on a post P' (Fig. 9) on which are screwed two blocks or disks Q', one of which has two slots S' for two parallel vertical 45 wires R', so that the pulley O' and its post P' are slidably mounted on the wires R'. A spring T' engages one of the blocks Q' and the head V' of the wires R' and constantly tends to yieldingly draw the pulley O' upward. By this means, the wire B is held 50 taut in its passage from the spool to the pulleys U and T.

The operation of the machine is as follows. When the armatures A are mounted in the 55 machine, as already described, a wire B is attached to each armature and the shaft I and spindle G rotated. This rotation rotates all the armatures simultaneously and the wires are drawn off the spools over the tension 60 pulley O' under and over the pulleys U and T and wound around the armatures. In order that the wire may be wound neatly and accurately, a lateral movement of the pulleys U and T is effected by means of the 65 sleeve Y, which, as has been pointed out, is

loosely mounted on the shaft Z. When, for example, the upper arm A' of the sleeve Y is engaged with the screw threaded rotary shaft C', the sleeve Y slowly travels toward the left and the wire wound, as suggested in 70 Fig. 2. When the wire is wound in one layer around the armature, the operator disengages the handle H' and swings the lever F' so that the other arm B' of the sleeve Y 75 engages the screw threaded rotary shaft C', whereupon the sleeve Y will travel in the opposite direction. As all the wires for the armatures pass over pulleys U and T mounted on supports on the sleeve, the lateral adjustment of all the wires is simultaneous. 80

If it is desired to stop the lateral movement of the guiding pulleys U and T, although the rotation of the armature is continued, the lug K' or L' is disengaged and the lever F' swung to a position where 85 neither of the arms A' or B' engages the screw threaded shaft C'. This will obviate any movement of sleeve Y and the lateral movement of the guide pulleys U and T. Upon the completion of the winding of the 90 armature, the machine is stopped and the wires severed. One of the end armature holders F is loosened, whereupon the springs S will tend to separate the brackets O and armature holders C to release the wound armature. 95

Having now described my invention (which may vary in its details without departing from the spirit thereof), what I claim and desire to secure by Letters Patent, is:

1. In an armature winding machine, the combination with a series of armature holders having a common axis of rotation and adapted to grip a plurality of armatures so 105 that said armatures will rotate on the same axis of rotation; of mechanism for rotating said holders, substantially as described.

2. In an armature winding machine, the combination with a series of armature holders having a common axis of rotation, and adapted to grip a plurality of armatures; of mechanism for rotating said holders; and means for simultaneously releasing the 110 armatures gripped by said holders, substantially as described.

3. In an armature winding machine, the combination with a series of pairs of armature holders having a common axis of rotation, each pair of holders being adapted to 120 grip an armature between them; of mechanism for rotating one or more of said holders; and a connection between adjacent holders of different pairs for transmitting the rotary movement of one pair to the other, substantially as described.

4. In an armature winding machine, the combination with non-rotary brackets; of rotary rings within said brackets; armature holders having bearings in said rings and 130

adapted to grip an armature to rotate therewith; and mechanism for rotating one of said holders, substantially as described.

5. In an armature winding machine, the combination with a series of non-rotary brackets; of armature holders arranged in pairs, each pair being adapted to grip an armature between them to rotate therewith, said holders having bearings in said brackets; and 10 mechanism for rotating said holders, substantially as described.

6. In an armature winding machine, the combination with non-rotary brackets capable of longitudinal movement; armature 15 holders mounted to rotate on said brackets, and arranged in pairs, each pair being adapted to grip an armature between them to rotate therewith; and mechanism for rotating said holders, substantially as described.

20 7. In an armature winding machine, the combination with a series of non-rotary brackets capable of longitudinal movement, of armature holders mounted to rotate on said brackets and arranged in pairs, each 25 pair being adapted to grip an armature between them to rotate therewith; springs normally tending to separate said brackets; means for holding said brackets against the 30 tension of said springs; and mechanism for rotating said holders, substantially as described.

8. In an armature winding machine, the combination with bars; of a series of non-rotary brackets mounted on said bars and capable of longitudinal movement thereon; of 35 springs for normally separating said brackets; of armature holders mounted to rotate on said brackets, and arranged in pairs, each pair being adapted to grip an armature between them to rotate therewith; means for 40 holding said brackets in their proper position against the tension of said springs; and mech-

anism for rotating said holders, substantially as described.

9. In an armature winding machine, the 45 combination with a series of non-rotary brackets; of armature holders arranged in pairs, each pair being adapted to grip an armature between them to rotate therewith; rotary shafts connecting adjacent holders of 50 different pairs and mounted to rotate on said brackets; and mechanism for rotating said holders, substantially as described.

10. In an armature winding machine, the combination with a pair of armature holders, 55 each having an angular recess adapted to receive one side of an armature to rotate the armature therewith; and mechanism for rotating said holders, substantially as described. 60

11. In an armature winding machine, the combination with a device for guiding wires to said armatures; of a frame; of a wheel 65 slidably mounted on said frame; and means for yieldingly holding said wheel in its proper position on said frame, said wheel being adapted to receive the wire from the spool to said guiding device, substantially as described.

12. In an armature winding machine, the 70 combination with a device for guiding wire to armatures; of a frame carrying parallel bars; a block slidably mounted on said bars; a wheel rotatably mounted on said block, adapted to receive the wire from the spool to 75 said guiding device; and a spring for yieldingly holding said block in its proper position on said rods, substantially as described.

In witness whereof, I have hereunto set my hand on the 12th day of June, 1905.

CHARLES H. LEWIS.
